ADJUSTABLE RIB

Hubert Tidwell, Washington, D. C.

Application February 18, 1944, Serial No. 522,954

3 Claims. (Cl. 189—34)

This invention relates to an adjustably variable stay or rib which is especially, but not necessarily, adapted for use as a flexible bow in the framework construction of an umbrella or other similar structure in which a covering of fabric or the like is taut in one position and collapsed in another position.

In reducing to practice the preferred embodiment of my invention and the specific principles adopted in the finished product, I have had in mind the construction of a special so-called pocket-type umbrella for personal use, that is, an umbrella embodying a skeleton frame-work composed of two semi-circular bendable bows or stays hingedly connected together, which stays could then be brought into adjacent overlapping relationship and, with the fabric, rolled into a compact bundle. However, the principal and only part in which I am presently interested is a novel bendable bow or stay which is convertible from a substantially rigid to a flexible state and vice versa.

More specifically, the invention relies for novelty on a flexible steel or equivalent metal rib-like bow construction, suitable for incorporation in the frame structure of collapsible pocket-type umbrella, but equally well employable in other lines of endeavor, the preferred representative embodiments being characterized by interconnected relatively shiftable coating parts which, when said parts are in a predetermined relationship the rib is flexibly rigid and bowable and, when said parts are in other relative positions the bow can, under such circumstances, be rolled into compact coiled form.

Other features and advantages will become more readily apparent from the following description and the accompanying illustrative drawings.

In the drawings, wherein like numerals are employed to designate like parts throughout the various views:

Figure 1 is a fragmentary end view, in elevation, showing one form of bow or rib constructed in accordance with the principles of the instant invention, the parts in this view being adjusted for rendering the overall unit substantially rigid.

Figure 2 is a view like Figure 1 showing the respective sections or parts shifted to coating positions to render the structure collapsible and rollable.

Figure 3 is a top plan view of the structure seen in Figure 1.

Figure 4 is a top plan view of the structure seen in Figure 2.

Figure 5 is a cross section on the plane of the line 5—5 of Figure 2.

Figure 6 is a perspective view of the inner slideable section.

5 Figure 7 is a perspective view of the outer relatively stationary enclosing or sheath section.

Figure 8 is an edge elevational view showing the sections relatively shifted to render the bow or rib flexible, whereby to permit it to be either flexed as shown or rolled into a complete compact coil.

Figure 9 is an elevational view showing how the convolutions or coils nest in spiral form when the complete bow is coiled or rolled upon itself.

15 Figure 10 is a view like Figure 1 showing a modified form of the invention, this being a flat cross-sectional type, as distinguished from the L-shaped cross-sectional type in Figure 1.

Figure 11 is a view like Figure 10 showing the 20 sections or parts shifted with certain portions registering to render the complete structure readily bendable and rollable.

Figure 12 is a view showing the reverse side of the structure depicted in Figure 10.

25 Figure 13 is a cross section on the plane of the line 13—13 of Figure 11.

Figure 14 is a fragmentary sectional and elevational view detailing the angularity and bendability of adjacent portions to bring out to better advantage the respective relationships and curvatures of parts.

30 Figure 15 is an edge view showing the rib in the process of being coiled or flexed into an arc less than a coil.

35 Figure 16 is a top plan view of the blank from which the inner slide section is fashioned.

Figure 17 is a flat plan view of the blank from which the outer relatively stationary sheath section is fashioned.

40 In the two modifications illustrated, one is L-shaped in cross-sectional form as shown in Figures 1 to 9, inclusive. The other is substantially flat in form as brought out in Figure 13. However, in both forms or types the principles and fundamentals are the same in that we have two telescopically connected sections, the outer section forming sort of a sheath, the inner section a core-like slide which shifts back and forth in the sheath.

45 The two sections are formed with slit break joint portions which when the slits register permit both sections to roll or bend freely as a unit. When the inner section is shifted to a position so that its edge portions bridge the slits in the edge portions of the outer or sheath section 50 the two sections become substantially rigid but

55 the two sections become substantially rigid but

only to a degree to permit the rib, as a unit, to bow. Thus, we have a flexible or bendable rib, or a rib which can be converted into one susceptible of being rolled into a substantially compact bundle, as brought out for example in Figure 9.

Attention is first directed to Figures 1 to 9, inclusive, illustrating the so-called L-shaped rib or bow. Although sheet material, generally speaking, is susceptible of use in constructing the bow or rib I prefer, obviously, to use a high grade steel. The drawings tend to exaggerate the size of the device but in practice, it will be much smaller, not quite as narrow as a stay or rib in present-day umbrellas. The outer relatively stationary section is denoted by the numeral 18 and the core-like inner shiftable or slide section is indicated at 19. Reference being had to the part 18 in Figure 7, it will be observed that it comprises a body or strip portion 20 having marginal flanges bent laterally as at 21 and inwardly as at 22 to form a longitudinally extending channel. This channel accommodates the laterally directed flanges 23 extending from one edge portion of the strip or body 20 of the inner slidable section 19. The respective sections 18 and 19 fit telescopically together in shiftable or reciprocatory relationship as shown in Figure 5. The cross section of the structure as a unit is substantially L-shaped as here disclosed. The edge portion of the part 18 adjacent the sheath-like channel is formed with T-shaped slots 25 and the portions of the slots severing the flanges or flange portion 21 are disposed in outwardly divergent relationship as indicated at the points 26 and 27. The coacting or companion section 19 is formed with corresponding T-shaped slots 25a and the flange portions 23 have the stem portions of the slots extending therethrough in diverging relationship as at 26a and 27a. Under this arrangement when the two sections 18 and 19 are disposed in telescoping relation the T-shaped slots of the respective parts can be brought into registry with one another as shown in Figure 2. This permits the existence of the desired degree of flexibility to allow the entire device to be rolled into a coil as shown in Figure 9. In rolling it the sheath portions stack upon one another so that the final rolled article or device assumes a somewhat helical form. When the respective T-shaped slots in the sections are disaligned, the solid portions 23 of the section 19 bridge the slot portions of the section 18, thus permitting the two sections to coact in providing for greater degree of rigidity. However, and even in the latter positions the two sections form a rib which can be forcibly flexed, endwise, into a bow, that is, an arcuate bow. In other words, even with the parts in the relationships shown in Figures 1 and 3, we still have a bendable rib susceptible of incorporation in an umbrella. In a sense we have a sectional rib of convertible type, that is, convertible from one which can be bowed longitudinally, or one which can be rendered sufficiently flexible when the parts are properly shifted to be rolled into a compact coil. In practice, the inner slide section is provided with a finger piece or operating element 29 with a bolt and nut 30 and 31, the bolt extending through a slot 32 so that it is possible to lock the sections either in "open" or "closed" positions or intermediate stages between the two extremes. Incidentally, and by way of further explanation the "closed" position is seen, for ex-

ample, in Figures 1 and 3, and the "open" position seen in Figures 2 and 4.

Referring now to the other form of the invention depicted in Figures 10 to 17, inclusive, we have the flat type rib or bow. The outer sheath section is here denoted by the numeral 33 and the inner slide or core section is denoted at 34. The section 33 is provided with inbent flanges 35 forming channels or sheaths for the edge portions of the inner section 34. The latter edge portions are also bent upon themselves as indicated at 36 in Figure 13. This is simply for sake of rigidity. The same slotting principle is also disclosed in these figures. That is to say, the outer relatively stationary sheath is formed with T-shaped slots 37 and the inner slide is provided with coacting or companion T-shaped slots 37a. The slots can be either registered or disaligned to provide the desired "open" and "closed" respective positions of said sections. It will be noted that by using parallel pairs of T-shaped slots and opening the slots through the opposite longitudinal edge portions of both sections, the portions of the band or body 38, that is, the areas indicated at the points 39 are relatively narrow highly flexible webs. It is the webs 39 which provide the desired flexing feature as brought out to advantage in Figure 14. In other words, the major segments are substantially rigid in themselves but the strap-like webs 39 between the rigid sections flex sufficiently to allow rolling or coiling.

Figures 16 and 17 are merely employed to bring out the configuration or formation of the two metal blanks from which the parts 33 and 34 are actually fashioned.

It will be seen from the foregoing that I have evolved and produced a sectional bow or rib which is susceptible of incorporation in a collapsible pocket type umbrella. However, and as before stated, I am primarily interested in the construction of the bow or rib per se and the fact that when the coacting telescoping sections are "closed" the two parts coact in forming the rib which has sufficient flexibility to bow longitudinally into an approximate half-circle. When, however, the parts are shifted to "open" position then they are sufficiently flexible to be rolled into a compact package as illustrated for example in Figure 9.

An adjustable bow of this type could be used in many different lines of endeavor since the sheath on the outside is in effect a track, and the inside part is a slide, and since it is possible to relatively adjust the two sections to regulate the degree of flexibility from a casual longitudinal bow to a convenient and compact coil.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A rib-like bow of the class described comprising a longitudinally elongated device embodying an exterior section including a lateral edge channel forming a sheath, a relatively movable section in slidable contact therewith and having a flanged portion adjustably mounted in

said sheath, the channel and flanged portion of the slide having coacting slots which can be brought into registry or shifted to disaligned positions to vary the degree of rigidity and/or flexibility in the manner and for the purposes described.

2. In a bow construction of the class described, a sheath having longitudinal channels on the opposite longitudinal edges and formed with opposed T-shaped slots having portions opening through the walls of the channel, and a slide having longitudinal edge portions adjustable in said channel and also having T-shaped slots movable

5 into and out of registration with the T-shaped slots in the sheath in the manner and for the purposes described.

3. A freely bendable rib-like bow of the class described comprising a longitudinally elongated device embodying an exterior section including a lateral edge slotted and coilable channel forming a sheath, a relatively movable section in 10 slidable contact therewith and having a flexible flanged portion adjustably mounted in said sheath to render the latter alternatively rigid and bendable at will.

HUBERT TIDWELL.
